HINGE

Andrew F. Wintercorn and Edward P. McCanna,
Rockford, Ill., assignors to The Atwood Vacuum
Machine Company, Rockford, Ill., a copartner-
ship composed of Seth B. Atwood and James
T. Atwood

Application August 2, 1937, Serial No. 156,916

6 Claims. (Cl. 16—135)

This invention relates to hinges generally, but is more particularly concerned with improved ball-and-socket type hinges for the doors of motor vehicles.

5 It is the principal object of our invention to provide hinges of the kind mentioned wherein the ball head has a swivel fit in a circular hole, or in an annular seat formed in a perforated or recessed part, whereby to obtain greater accuracy at lower cost and with less difficulty in the process of manufacture.

10 Another important object of our invention is to provide hinges of the kind mentioned having the socket part of stamped sheet metal construction.

15 Still another object is to provide hinges of the kind mentioned wherein both the ball head member and socket member are of stamped sheet metal construction.

20 These and other objects of the invention will appear in the course of the following detailed description in which reference is made to the accompanying drawing, wherein—

25 Figs. 1 and 2 are a horizontal and vertical section, respectively, through a portion of a door pillar and door, showing a concealed ball-and-socket type hinge wherein the ball and socket parts are both of stamped sheet metal construction, Fig. 2 being taken on the line 2—2 of Fig. 1;

30 Fig. 3 is similar to Fig. 2, but shows a further variation, while Fig. 4 is a sectional detail on the line 4—4 of Fig. 3, and

35 Figs. 5 and 6 are views similar to Figs. 1 and 2, but showing the reverse arrangement of the ball and socket members with relation to the door pillar and door.

Similar reference numerals are applied to corresponding parts throughout the views.

In Figs. 1 and 2, two sheet metal stampings 62c and 67c are bolted, as at 41e, to the wall of the body pillar 25e. The plate 62c has a lug 61c bent substantially at right angles thereto, while the plate 67c has a lug 66c bent substantially at right angles thereto, and between these lugs the ball head 80a of the gooseneck member 28a is adapted to be retained and supported for swivel movement. The projecting lugs on the two plates are formed to provide hollow cylindrical bosses, as at 74, and countersunk or chamfered to provide the annular seats 51 to fit the ball head.

40 Now, the gooseneck member 28a is formed from two sheet metal stampings 75 and 76 substantially L-shaped with one end stamped to hollow semi-spherical shape, as indicated at 77, while the other end is bent at right angles, as at 78, to provide 45 attaching lugs arranged to be bolted to the wall

of the door frame member 45e, as indicated at 79. A tapping plate 80 is provided and the bolts 79 extend through vertical slots 81 in the door frame to thread in the tapping plate. The wall abutting face 82 on the lug 78, as well as the wall 5 abutting face 83 on the tapping plate, are preferably serrated so as to take good hold when the bolts 79 are tightened. For a similar reason, the wall abutting faces 82' of the plates 62c and 67c are serrated, and it will be noticed that the bolts 10 41e extend through horizontal slots 81' in the wall of the body pillar member 25e to permit in and out adjustment of the socket. The pieces 75 and 76 are both ribbed longitudinally, as at 84, between the ball head end and the attaching 15 end for reinforcement and to lend stiffness, and the pieces may be riveted together, as indicated at 85. If desired, absorbent wick material may be provided inside the ball head 30a, as indicated at 86, and an oil hole 87 may be provided in one 20 half of the ball head, and another oil hole 88 in the upper half of the socket to supply lubricant to the ball and socket joint. An additional hole may be provided, if desired, as indicated at 89 in the lower half of the ball head to insure lubrication of the lower half of the socket, although it is believed that sufficient lubricant will seep through the joint in the ball head to furnish adequate lubrication for both halves of the socket. 25 Since the ball head or gooseneck member 28a is 30 vertically adjustable while the socket parts are horizontally adjustable, it is clear that the present construction makes the door universally adjustable in the door opening, and there is therefore no difficulty in centering the door and lining 35 it up with the body and with a companion door. The manufacture of the ball head or gooseneck member of sheet metal construction results in a substantial saving in cost, and the cost is low enough to be competitive with the old style pintle 40 hinges. The hinge is moreover easily assembled on the doors and pillars of motor cars as now constructed. The construction is furthermore self-centering and there is definite assurance of a complete circle of bearing contact between the 45 ball head and the seats 57 therefor, the present construction accordingly eliminating the necessity for keeping the production of ball heads within close limits, whereas with other constructions providing spheroidal-shaped depressions for reception of the ball head, it was obviously important 50 to have the ball head and socket parts made accurately to fit one another. Slight "run out" in the production of the ball heads with the present construction is practically unnoticeable by reason 55

of the self-centering. Two hinges of the kind described will be provided on each door in vertically spaced relation, it being obvious that the two points thus fixed by the balls and sockets are sufficient to determine the hinging axis of the door and provide for smooth and uniform operation throughout the range of opening movement. Hinges of the present construction will not bind nor develop play and give rise to door rattling like the old style pintle hinges.

Figs. 3 and 4 show a variation of the construction of Figs. 1 and 2, in which the ball head 30b has the two halves 77' thereof perforated, as at 90, for the passage of a bolt 91 diametrically therethrough, the bolt being entered through holes in the lugs 61d and 66d on the plates 62d and 67d, respectively. Obviously with such a construction there is increased strength as a result of the bolting together of the two halves of the socket, and of course the holes 90 may be provided large enough in relation to the diameter of the shank of the bolt 91 to allow ample angularity of universal movement of the ball head relative to the socket. It is understood, of course, that the plates 62d and 67d may be bolted or otherwise suitably secured to the wall of the body pillar. The two parts 75' and 76' of the gooseneck member 28b are ribbed longitudinally at 84 similarly as in the previous construction, and are riveted together as at 85. If desired, an oil hole may be provided in the lug 61d next to the ball head, as at 88', to furnish lubricant to the ball-and-socket joint, and, if desired, absorbent wick material may be provided inside the ball head 30b to retain lubricant. The advantages and operation of this construction are similar to what is obtained with the construction of Figs. 1 and 2.

Figs. 5 and 6 show a hinge construction having the reverse arrangement of the ball and socket members with relation to the body and pillar from that disclosed in Figs. 1 and 2. Here the ball head 30c is formed by the semi-spherical ends of plates 62e and 67e, bolted as at 41f to the body pillar 25f, while the gooseneck member 28c is formed similarly as the gooseneck members 28a and 28b except that the outer ends 74' of the two halves 75c and 76c are recessed and provide seats 57 therein for the ball head 30c. An oil hole 88a in the upper half of the socket formed on the outer end of the gooseneck member 28c permits supplying lubricant to the ball and socket joint, and an oil hole 87a may be provided in the upper half of the ball head 30c and absorbent wick material 86a may be provided inside the ball head to provide for similar lubrication as with the hinge of Figs. 1 and 2. An additional oil hole may be provided in the lower half of the ball head, as at 89a, if desired. It is obvious that substantially the same advantages are obtained with this construction as with the construction of Figs. 1 and 2.

It is believed the foregoing description conveys a good understanding of the objects and advantages of our invention. The appended claims are drawn with a view to covering all legitimate modifications and adaptations.

We claim:

1. In a hinge construction, the combination of a ball head member comprising a generally L-shaped substantially horizontal shank terminating in a ball head at one end and a substantially vertical attaching portion at the other end adapted to be attached to one of a door and body in mounting the door on the body of a vehicle, and a socket for said ball head comprising a pair of sheet metal angular attaching plates each comprising an attaching portion in a substantially vertical plane for attachment to the other of said door and body and a socket portion disposed in a substantially horizontal plane substantially at right angles thereto and projecting from the attaching portion in a direction away from the attaching portion of the ball head member, the socket portion having a circular socket recess provided therein for swivel reception of a portion of the ball head therein, said attaching plates being disposed with the socket portions on diametrically opposite sides of the ball head, and with the attaching portions fixedly mounted in vertically spaced relation so as to permit swinging movement of the L-shaped shank of the ball head member therebetween.
2. A hinge as set forth in claim 1, wherein at least the head end of the ball head member is formed from two pieces of sheet metal, the ball head being formed by two dished portions placed with the rims thereof in edge to edge abutment with one another, the hollow ball head thus formed constituting a lubricant reservoir, said head having a filling of absorbent material between the halves thereof, and one of the aforesaid socket portions having an oil hole provided therein, and at least one of said semi-spherical end portions having an oil hole provided therein communicating with the oil reservoir.
3. A hinge as set forth in claim 1, wherein the ball head member is formed from two L-shaped pieces of sheet metal with the ball head formed by two dished end portions of said pieces placed with the rims thereof in edge to edge abutment with one another, the shank portions of both pieces being formed to substantially channel-shaped cross-section to provide longitudinal reinforcing and stiffening ribs projecting in opposite directions relative to one another when the pieces forming the ball head member are placed edge to edge in assembled relation.
4. In a hinge construction, the combination of a ball head member comprising a generally L-shaped substantially horizontal shank terminating in a ball head at one end and a substantially vertical attaching portion at the other end adapted to be attached to one of a door and body in mounting the door on the body of a vehicle, and a socket for said ball head comprising a pair of sheet metal angular attaching plates each comprising an attaching portion in a substantially vertical plane for attachment to the other of said door and body and a socket portion disposed in a substantially horizontal plane substantially at right angles thereto and projecting from the attaching portion in a direction away from the attaching portion of the ball head member, the socket portion having a circular socket recess provided therein for swivel reception of a portion of the ball head therein, said attaching plates being disposed with the socket portions on diametrically opposite sides of the ball head, and with the attaching portions fixedly mounted in vertically spaced relation so as to permit swinging movement of the L-shaped shank of the ball head member therebetween, the ball head having a diametrically extending vertical hole provided therein and a substantially vertical fastening bolt having a shank of reduced diameter in relation to the diametrical hole in the ball head extending from one socket portion through the hole in the ball head into the other socket portion and serving when tightened to draw said socket portions toward one another.

5. A hinge as set forth in claim 1 wherein each of the sheet metal angular attaching plates has a hollow substantially cylindrical boss provided on the socket portion wherein the circular socket recess is provided for swivel reception of the ball head, said boss having an end wall substantially parallel to and spaced from the rest of the socket portion and adapted to lie in spaced relation to the ball head received in the socket recess, there 10 being a spheroidal circular seat provided in the other open end of said boss adapted slidably to engage the ball head.
6. As an article of manufacture, a socket member for a ball and socket hinge comprising a sheet metal body of angular form providing an attaching portion in one plane for attachment to one 15 of a door and body in mounting a door on the body of a vehicle, and a socket portion in a transverse plane substantially at right angles to the attaching portion, the socket portion having a hollow cylindrical boss provided thereon, the 5 boss having an end wall in parallel spaced relation to the rest of the socket portion, and said socket portion having a spheroidal circular seat provided therein in concentric spaced relation to said end wall adapted to have slidable engagement with a ball head, said seat being so spaced in relation to said end wall that the ball head adapted to engage the seat will lie in spaced relation to the end wall.
